SLIP OR THE LIKE

Dixie Howell, McComb, Miss., assignor to McComb Manufacturing Company, McComb, Miss., a corporation of Mississippi

Filed Feb. 12, 1960, Ser. No. 59,368

Term of patent 14 years

(Cl. D3—26)

Fig. 1 is a front elevational view of a slip, showing my new design; and

Fig. 2 is a fragmentary rear elevational view thereof. Parts of the slip are shown broken away for convenience of illustration, said broken away parts being conventional and substantially plain.

I claim:

The ornamental design for a slip or the like, as shown and described.
